DUPLICATOR

Shinjiro Horii, Kanda-ku, Tokyo, Japan

Application November 26, 1935, Serial No. 51,670
In Japan December 7, 1934

2 Claims. (Cl. 101—126)

This invention relates to a duplicator, more particularly to a flat duplicator of the type in which a stencil stretching frame is swingably connected at one end to a bed of the duplicator.

- 5 One object of the invention is to provide a duplicator of this type in which the position of the stencil stretching frame relative to the bed can be readily adjusted in either direction in horizontal plane.
- 10 A further object of the invention is to provide a simple construction of the device for adjusting the printing position of the stencil stretching frame relative to the bed, in which a manipulation of a single part releases and tightens said 15 adjusting device.

With the above-mentioned objects in view, the duplicator according to the invention comprises a bed, a stencil stretching frame having trunnions, a supporting block having brackets formed with bearing slots adapted to be engaged by said trunnions on the stencil stretching frame, means for mounting said supporting block on the bed portion in manner that it may be slid in both longitudinal and transverse directions, and releasable 25 means for securely uniting said supporting block and the bed.

In the accompanying drawing illustrating one form of the invention:

Figure 1 shows in vertical section a duplicator according to this invention;

Figure 2 is a plan thereof, partly broken away;

Figure 3 shows a side view on somewhat enlarged scale of the hinge portion of the duplicator; and

Figure 4 is a section taken on line IV—IV of Figure 2.

Referring to the drawing, 1 is a bed of the duplicator, which has a rear extension or foot 2 offset downwardly from the main portion. The 40 front end (right hand end in Fig. 1) of the bed 1 is supported by another foot (not shown). The rear foot 2 is provided with two channels 3 and 4 which are arranged longitudinally of the duplicator, as shown in Figure 2. Said channels are 45 covered by rail bars 5 and 6 respectively, each of which bars is formed with a guide slot 7 open toward the rear end. A spring bar 8 is provided at both ends with pins 9 and 10 which are engaged by the guide slots 7 formed in the bars 5 and 6. 50 In order to prevent the pins 9 and 10 from being removed upwardly out of the guide slots 7, the pins 9 and 10 are formed with heads 11. At the mid point, the spring bar 8 is provided with a shank 12 extending upwardly and screw threaded 55 at the upper end. Movable mounted upon the

rear foot 2 is a supporting cross member or block 13 which is formed with a slot 14 arranged transversely of the duplicator. The shank 12 is passed through said transverse slot 14, and a thumb nut 15 is screwed on the projected upper end of the shank 12. It will be seen that by unscrewing the nut 15 the supporting block 13 is permitted to be slid in either direction, but that when the nut 15 is tightened the spring bar 8 is pulled upwardly so that the heads 11 of the pins 9 and 10 are pressed against the under sides of the guide rails 5 and 6, whereby not only the shank 12 is secured in the transverse slot 14, but also the ends of the spring bar 8 are pulled upwardly and the heads 11 of the pins 9 and 10 are pressed against the under sides of the guide rails 5 and 6, so that the supporting block 13 is locked against any movement relative to the foot 2.

The supporting block 13 is provided with brackets 16 secured one on each end thereof. Each of said brackets 16 has a vertical bearing slot 17. 20 18 is a stencil stretching frame and is provided with an extension arm 19 secured on each side thereof near the rear end. Said extension arm 19 carries trunnion 20 which is adapted to be slidably mounted in said bearing slot 17, so that the stencil stretching frame 18 is swingably connected to the supporting block 13 fixed to the bed 1.

Pivoted at 21 to the bracket 16 is a lever 21 which is provided on one arm with a nose 22 adapted to partially close the mouth of the bearing slot 17 and to prevent unintentional removal of the trunnion 20 therefrom when the stencil stretching frame 18 is in its lowered position as shown in Figure 3. On the other arm, the lever 21 is provided with a projection 23. On each side of the stencil stretching frame 18, preferably on the root portion of the extension arm 19, is a pivoted arm 24 which has on its free end a projection 25. A compression spring 26 is connected to said projections 23 and 25, said spring normally tending to lift the stencil stretching frame 18 when the lever 21 and arm 24 are in the position shown in Figure 3, i. e. when the free end of the arm 24 is turned rightwardly and slightly downwardly. 27 is a stop limiting the downward movement of the arm 24. When the arm 24 is turned upwardly and leftwardly from the position shown in Figure 3, the tension of the spring 26 is released, so that the stencil stretching frame 18 may be manipulated without the influence of said spring 26, and it may be kept in its lowered position by gravity and without necessity of being pressed by hand. The lever 21 is normally held in fixed position with respect to the bracket 16 55

by suitable means not shown. In the position shown in Figure 3, when the lever 21 is turned counter-clockwise and held by suitable means (not shown) in the position shown by dot-and-dash line 28, the line of action of the spring 26 will be moved closer to the axis of swing (trunnion 20) of the stencil stretching frame, so that the lifting action of the frame 18 becomes semi-automatic. In other words, the frame 18 is held in its lowered position without necessity of being pressed by hand, and yet when an initial lifting pressure is applied thereto by hand the frame will be lifted by spring action.

For the sake of simplicity the arrangement of the parts has been described with reference to only one side of the duplicator, but it is to be understood that the device on the opposite side is similarly constructed.

In the duplicator according to this invention, the position of the stencil stretching frame 18 relative to the bed 1 in horizontal plane can be altered in any direction by releasing the supporting block 13 so as to be slid in longitudinal as well as transverse directions relative to the foot 2. And such release may be effected merely by unscrewing the nut 15 only, so that the adjustment of the printing position may be readily effected at will.

What I claim is:—

1. A flat duplicator comprising a bed having an extension provided with two longitudinal guide

slots, a stencil stretching frame having trunnions, a supporting block having brackets formed with bearing slots adapted to be engaged by said trunnions on the stencil stretching frame and provided with a transverse guide slot, a spring bar 5 having at both ends pins engaged by said longitudinal guide slots in the bed extension and having a central shank extending upwardly through said transverse slot in the supporting block, and means for tightening said spring bar and its shank together with the bed extension and supporting block.

2. A flat duplicator comprising a bed having an extension provided with two longitudinal guide slots, a stencil stretching frame having trunnions, a supporting block having brackets formed with bearing slots adapted to be engaged by said trunnions on the stencil stretching frame and provided with a transverse guide slot, a spring bar 15 having at both ends pins engaged by said longitudinal guide slots in the bed extension and having a central shank extending upwardly through said transverse slot in the supporting block, means for tightening said spring bar and its shank together with the bed extension and supporting block, 20 springs connected between the supporting block and the stencil stretching frame for automatically lifting the stencil stretching frame, and means for rendering said springs ineffective.

SHINJIRO HORII.
